UNITED STATES PATENT OFFICE

2,437,529

FUEL INJECTOR

John H. Holloway, Green Bay, Wis., assignor to
 Northwest Engineering Company, Green Bay,
 Wis., a corporation of Wisconsin

Application June 23, 1943, Serial No. 491,892

4 Claims. (Cl. 103—41)

1

The invention relates to fuel injectors for internal combustion engines and more particularly to the so-called unit injector in which the atomizer or sprayer is substantially directly connected with the discharge of the pump.

One of the objects of the invention is to improve the arrangement of the injector parts, so that the pump plunger and its barrel are of relatively short length and disposed at the upper end of the head of the engine while the sprayer is at the bottom of the head and connected with the pump barrel by a small or capillary passage, so that the clearance volume of the pump is not increased over former structures and the metering pump structure is greatly simplified and less special material need be used.

A further object of the invention is to improve the metering pump to permit changing in the timing of the injection with means for accurately adjusting the timing of individual injectors.

A further object of the invention is to provide for the drive of the pump plunger from a pair of cam operated levers with means for equalizing the thrusts on the plunger from said levers.

A further object of the invention is to provide a simple and effective pump discharge valve mechanism.

A further object is to improve the by-pass control mechanism for the injector.

The invention further consists in the several features hereinafter set forth and more particularly defined by claims at the conclusion hereof.

In the drawings:

Fig. 1 is a vertical sectional view through a device embodying the invention taken on the line 1—1 of Fig. 2;

Fig. 2 is a horizontal sectional view taken on the line 2—2 of Fig. 1;

Fig. 3 is a vertical sectional view taken on the line 3—3 of Fig. 2;

Fig. 4 is a vertical sectional view taken on the line 4—4 of Fig. 2;

Fig. 5 is a detailed horizontal sectional view taken on the line 5—5 of Fig. 4;

Fig. 6 is a detailed horizontal sectional view taken on the line 6—6 of Fig. 4;

Fig. 7 is an enlarged vertical sectional view of the discharge end of the injector;

Fig. 8 is a detailed side elevation view of the discharge valve spring seat member;

Fig. 9 is a plan view of the seat member shown in Fig. 8;

Fig. 10 is a detailed horizontal sectional view through the spray nozzle;

2

Fig. 11 is a detailed horizontal sectional view taken on the line 11—11 of Fig. 3;

Fig. 12 is a detailed horizontal sectional view taken on the line 12—12 of Fig. 3.

5 Referring to the drawings, the numeral 15 designates portions of a cylinder head of an internal combustion engine and 16 an injector mounting sleeve which has threaded engagement at 17 with the lower wall of the head and ring sealed engagement at 18 with the upper wall of the head. An injector mounting plate 19 also forms a part of the cylinder head structure and is provided with a bore 20 in which a tubular nut 21 is rotatably mounted, said nut having a gear 22 secured thereto meshing with a manually rotatable gear 23 journaled in the head part 19 and socketed to engage with a manually operable turning wrench 24.

The fuel injector includes a body member 25 and a casing member 26 which have threaded engagement with each other at 27 to form a housing and are locked in this engagement by a lock nut 28 and sealed against fuel leakage by a suitable compressible sealing ring 29. The member 26 is threaded at its lower end 30 to receive the sprayer clamping nut 31.

The casing member 26 is tubular, is threaded on the outside at 32 to engage the threads of the nut 21, has a pump barrel receiving cylindrical recess 33 in its upper end, a discharge passage 34 in its lower end and a bore 35 connecting said recess and passage and filled by a tube 36 having a small bore or capillary passage 37 formed therein.

35 A pump barrel 38 seats on the bottom of the recess 33 and is shouldered at its upper end 39 to receive a flange forming ring 40 whose outer top portion abuts an annular clamping shoulder 41 formed on the body member. With this arrangement when the housing parts 25 and 26 are screwed together, the barrel 38 and ring 40 are clamped between them. Fixed positioning of the barrel relative to the body member 25 is obtained by a removable pin 42 connecting the barrel 38

40 to the ring and a key connection between said ring and body formed by a vertical slot 43 in the ring engaged by the inner pin end of a bolt 44 mounted in the body 25. A fuel impact wear sleeve 45 is mounted in the recess 33 between its side wall and the barrel 38 from which it is spaced so as to provide an annular fuel receiving space 46 including the tapered wall upper portion of the member 26. The barrel has an inlet port 47 and a relief port 48 longitudinally spaced there-

45 from.

A metering pump plunger 49 is mounted to reciprocate in the bore of the barrel and has a control edge 50 at its outer or lower end adapted to cooperate with the port 47 to control the beginning of injection and a groove 51 provided with a control edge 52 to cooperate with the port 48 to control the by-passing of fuel from the pump chamber to the fuel supply. The groove 51 communicates with the pump chamber through a longitudinal bore 53 entering the front end of the plunger and connected with said groove by a cross bore 54. The control edge 50 is formed to change the time of the beginning of injection with the amount of fuel injected. Thus injection will begin earlier for a heavier or full load charge than for a light or half load charge. The control edge 52 is formed to terminate the injection after the desired charge of fuel has been delivered. The particular timing and the amount of the charge is determined by the angular position of the plunger 49 relative to the ports 47 and 48 as different portions of said control edges 50 and 52 cooperate with said ports in different angular positions of the plungers. There are oppositely disposed sets of control edges 50 and 52, so that one set may be used after the other wears down so as to provide efficient metering. Other porting arrangements may be used with the general arrangement of parts herein described.

The plunger 49 may be reciprocated by any suitable engine controlled drive mechanism but is preferably moved downwardly by a pair of spaced engine driven cams 55 each engaging a roller 56 of a tappet lever 57 pivotally mounted on the shaft 58 carried by the body member 25 and having its inner end 59 engaging a half ball 60 seated in a spherically recessed block 61 mounted in a recess 62, formed in the flanged bottom 63 of a spring connector member 64, the flanged upper end 65 of the plunger fitting in and seating on said flanged bottom 63. The connector member 64 is in the form of a tube slidably mounted in a bore 66 in the body 25 and provided with diametrically disposed clearance slots 67 for the levers 57. The upper end of the tube 64 has a spring seat collar 68 mounted thereon and secured against release by a locking ring 69 engaging in an annular groove 70 in said tube. Plunger return springs 71 and 72 are interposed between the top of the body 25 and the collar 68 and act to hold the lower end of said tube, the block 61, and the bearing member 60 in operative association with the levers 57 whose other ends are at the same time held against their operating cams 55. With this arrangement the cams 55, whose shafts 55' are suitably driven from the crank shaft of the engine through gearing connections (not shown), act on the levers 57 to swing them downwardly and thus move the pump plunger 49 downwardly on its injection stroke and then allow the plunger to be returned or moved upwardly by the springs 71 and 72.

For shifting the angular position of the plunger 49, it is provided with a cylindrical upper portion 73 on which a gear 74 is non-rotatably slidably mounted as by engaging a flat on said portion (see Fig. 12) and which gear meshes with a shiftable segmental gear 75 whose sleeve-like hub 76 is mounted to oscillate on a shaft 77 vertically supported intermediate its ends in the body 25. Angular movement of the hub 76 is limited by a stop pin 78 carried by the body and extending into an arcuate slot 79 in said hub.

The hub 76 has an operating arm 80 mounted to rotate thereon between a shoulder 81 and a

washer 82 secured in position by a nut 83 engaging the upper reduced threaded end of the shaft 77. This arm is adapted to be secured in different angular positions relative to the sleeve 76 by means of a pair of oppositely disposed set screws 84 carried by said arm and adapted to engage oppositely disposed stop surfaces 85 on the sleeve hub 76 formed by one of the sides of slots 86 in said hub. Thus by screwing in on one of the set screws 84 and loosening up on the other, the hub 76 is shifted angularly relative to the operating arm 80 and the gear 74 turned slightly to determine the exact position of the plunger 49 relative to the inlet port 47. The screws 84 are locked in adjusted position by lock nuts 84'.

The arm 80 is removably connected to a longitudinally movable control rod 86 by a recessed wear block 87 secured to said rod and engaged by a pin 88 slidably mounted on said arm and normally urged to operative position by a spring 89 and adapted to be manually released by a pulling up on the capped end 90 of said pin. With this arrangement reciprocation of the rod 86 acts through the block 87 and pin 88 to oscillate the arm 80 and consequently the gear 74 associated with it.

The gear 74 is held against longitudinal movement by the flange block 40 at one end and a thrust washer 91 at the other and held in the body 25 by a split ring 92 engaging in a groove 93 in said body. The plunger slides down into position in the barrel and the gear 74 in assembling the device.

For supplying fuel to the pump barrel means are provided for continuously circulating fuel through the space 46 and shown more particularly in Figs. 4, 5, and 6. In Fig. 5 there are drilled fuel supply passages 94 and 94' intersecting opposite sides of a vertically disposed bore 95 in the part 19, one of these passages being connected with the discharge side of a fuel circulating pump (not shown) and the other with the suction side of such pump. The lower end of the shaft 77 removably fits in the bore 95 and has a vertically extending bore 96 divided at its lower end by a partition member 97 into two lateral passages 98 and 99, the passage 98 communicating with an air chamber 100 formed by the upper end of said bore 96. The bore 95 is sealed against fuel leakage by a conical rubber-like sealing ring 101 yieldingly held against the shaft 77 and a seat 102 at the upper end of the bore by a follower ring 103 and a spring 104 interposed between said ring 103 and the part of the body 42 in which the intermediate portion of the shaft 77 is mounted and secured. The passage 98 is connected at its lower end by a hole 105 in shaft 77 with the inlet passage 94 and at its upper end by a hole 106 in said shaft with a chamber 107 in the member 25.

The passage 99 is connected at its lower end by a hole 108 in the shaft 77 with the outlet passage 94' and at its upper end by a hole 109 in said shaft with a chamber 110 in the member 25. Each chamber 107 and 110 is closed at its outer end by a screw plug 111 and at its inner end has a strainer 112 mounted therein and secured in position by a spring 113 interposed between said strainer and plug. The inner end of the chamber 107 is connected to the chamber 46 by a passage 114, and the inner end of the chamber 110 is connected to the chamber 46 by a passage 115. As a result of this construction fuel from the supply line enters the chamber 46 from the passage 114, and

some of it is withdrawn or flows back to the suction side of the supply through the passage 115.

It is to be noted that since the shaft 77 is fixed to the body member 42, it is removable with said member when the casing 26 of said injector is unscrewed from the nut 21.

The pump discharge valve and spray nozzle or sprayer may be of any suitable construction, but the specific form shown in detail in Fig. 7 is preferred. In this figure, the numeral 118 designates a valve seat disk abutting the lower end of the casing 26 and 117 a nozzle member whose upper flanged end 118 abuts against the disk, these parts being secured in tight clamping engagement with each other and with the casing by the clamping nut 31 having the inwardly extending flange 119.

The nozzle member 117 has a passage formed by concentric bores 120 and 121 extending from its upper end down to its tip 122 where the bore 121 is intersected by a plurality of radially disposed spray openings 123 drilled in said tip. The bores 120 and 121 form a conically walled shoulder 124 on which the lower conical end of a spring seat and valve stop member 125 is mounted, said member having intersecting inclined grooves 126 cut or formed in its lower end to provide communication between the bores 120 and 121.

A discharge valve 127 controls the flow of metered fuel through the passage 128 in the disk 116 which communicates with the passage 34 in the casing member 26 and is preferably in the form of a flat faced disk 129 seating on the flat seat disk 116 and which may have a spring guide and stop portion 130 that cooperates with the member 125 to limit the lift of the valve to a small amount, a spring 131 being interposed between the head of said valve and the member 125 to normally hold said valve in closed position.

With this construction the injector is mounted on the engine by inserting the casing 26 down through the nut 21 and into the tube 16 and the shaft 77 into the bore 95, which brings the pin 88 in line with the notch in the block 87, and then turning the nut 21 through the gears 22 and 23 to screw the casing 26 into said nut and bring the lower end of the nozzle clamping nut 31 into sealing engagement with a gasket 116 seated at the lower end of tube 16 to provide a gas-tight joint between the lower end of the injector and the head. When the fuel circulating pump is started, the fuel will be delivered to the space 46 adjacent the ports 47 and 48 in the barrel, and then when the engine is started, the rotating cams 55 and the springs 71 and 72 will cause the reciprocation of the plunger 49 in cyclic synchronism with the engine. On its down stroke the plunger 49 which on its suction stroke has uncovered the port 47 to admit a charge of fuel into the barrel 38 forces this fuel from the lower end of the barrel through the clearance passages 37, 34, and 128 past the loaded discharge valve 127 through the bores 120 and 121 and out through the spray passages 123 in a finely atomized spray. The amount of the sprayed charge will depend upon the annular setting of the plunger 49 relative to the barrel 38 to cause opening up of the by-pass port 48 sooner or later in the expressing stroke of the plunger. The control surfaces permit the adjustment of the plunger from a no-delivery to a full delivery position.

With this arrangement the metering parts of the pump are formed as a small compact unit in which difficulties due to bending and wrapping of the plunger have been substantially eliminated without interfering with the efficient metering

and delivery of the fuel to and through the sprayer at the lower end of the injector. By the term "capillary" as applied to the passage 37 I mean a passage with a diameter between one-thirty-second and one-sixteenth of an inch, so that while this tube may be made long in case of a relatively deep engine head, the over-all clearance of this passage is very small, so that the volumetric efficiency of the pump is not impaired.

10 The timing of the beginning of injection may be accurately determined through the setting of the gears 14 and 15, and the gear 15 is prevented by the stop 78 from being turned beyond the desired limits of its adjustment. The half ball bearing 60 seated in the block 61 equalizes the thrusts from the levers 59 and permits efficient drive of the pump plunger 49 even though one of the levers 59 may lag slightly relative to the other.

20 I desire it to be understood that this invention is not to be limited to the specific form or arrangement of parts above described except only in so far as such limitations have been included in the claims.

25 What I claim as my invention is:

1. In a fuel injector, the combination of a casing member, a pump barrel with a plunger working therein mounted in said member, a body member secured to said casing member, a pair of oppositely disposed plunger operating levers carried by said body member for moving the plunger in its delivery stroke, a thrust member having a spherically curved bearing surface connected with said plunger and a flat surface engaged by said levers, and spring means mounted on said body member and operatively connected to said thrust member to move the plunger on its return stroke.

40 2. In a fuel injector, the combination of a casing member, a pump barrel with a plunger working therein mounted in said member, a body member secured to said casing member, a pair of oppositely disposed plunger operating levers carried by said body member to move the plunger on its delivery stroke, a thrust member having a spherically curved bearing surface and a flat surface engaged by said levers, a sleeve member slidably mounted in said body member and carrying said thrust member and connected to said plunger, and spring means constantly urging said sleeve member to provide a bearing contact between said bearing member and said levers.

45 3. In a fuel injector, the combination of a casing member, a valve controlled passage at one end of the casing, a pump barrel with a plunger working therein in the other end of said member, a body member secured to the barrel receiving end of said casing member and having a bore aligned with said plunger and oppositely disposed slots 50 communicating with said bore, said plunger having a flanged outer end, a sleeve member slidably mounted in said bore and having an inwardly extending flange at its lower end on which the flanged end of said plunger seats, a bearing block mounted in said sleeve and engaging the flanged end of said plunger and having a spherically curved recess, a half ball seated in said recess, oppositely disposed cam operated levers pivotally mounted in said slots in said body member and projecting into the bore in said sleeve and engaging the flat side of said half ball, and spring means constantly urging said sleeve member to a bearing contact with said bearing block.

55 4. In a fuel injector, the combination of a housing having a pump barrel mounted therein,

a pump plunger working in said barrel, said plunger having a control edge and said barrel having a port cooperating with said control edge, means for adjusting the angular position of the plunger relative to said port including an oscillatory member, a shaft supported by said housing on which said oscillatory member is mounted, said shaft having a bore whose upper end forms an air chamber, a partition in said bore dividing it into two passages one of which communicates with said air chamber, means for connecting said two passages with the port in said pump barrel, and means for connecting said two passages with a source of fuel supply.
